UNITED STATES PATENT OFFICE.

SAMUEL J. WISDOM, OF MONTGOMERY, ALABAMA.

JACK.

SPECIFICATION forming part of Letters Patent No. 292,725, dated January 29, 1884.

Application filed October 3, 1883. (No model.)

To all whom it may concern:

Be it known that I, SAMUEL J. WISDOM, of 5
Montgomery, in the county of Montgomery
and State of Alabama, have invented a new
and Improved Jack, of which the following is
a full, clear, and exact description.

The object of my invention is to obtain a
compact and powerful jack or purchase for re-
moving piston-rods from the cross-heads of
10 steam-engines and for other purposes.

Reference is to be had to the accompanying
drawings, forming part of this specification, in
which similar letters of reference indicate cor-
responding parts in all the figures.

15 Figure 1 is a perspective view of my jack.
Fig. 2 is a view of part of a cross-head with
the jack in position as in operation. Fig. 3
is a sectional view taken on line *x x* of Fig. 2,
and showing part of a cross-head with the jack
20 in position as in operation. Fig. 4 is another
sectional view similar to Fig. 3, but showing
another form of jack adapted to longer dis-
tances.

25 My invention consists of a convenient mech-
anism for applying great power in contracted
spaces without danger of damage from ham-
mering or bruising the finished parts of the
machinery. I use a block of steel or iron, A,
30 in which is fitted a screw-bolt, D, having a
head by which it can be turned, and a pointed,
inclined, or rounded end, d. At right angles
to this bolt is fitted a movable pin or plug, E,
which is inclined or rounded upon its inner
35 end, where it comes in contact with the end
of the bolt D, so that when the bolt D is screwed
down the plug E is forced out. The side of the
block A opposite to the plug is hollowed or
forked, so that it may rest firmly against the
40 cross-head pin b, while the plug E bears against
the end of the piston-rod C, as shown in Fig.
3. Several plugs may be used in one block,
all operated by one screw in the same manner
as the plug E. In some cases—as, for exam-
45 ple, where the distance between the end of the
piston-rod and the cross-head pin will per-
mit—I use also another plug, e, similar to E,
the plug e having a forked head to bear against
the cross-head pin, and the inner end inclined

or rounded, so as to be acted upon by the bolt
D in the same manner as the plug E, as shown 50
in Fig. 4.

The operation of my jack is as follows: The
bolt D is screwed back, so that the plug E can
be pushed in. The block A is placed, as shown
in Figs. 2 and 3, between the ends of the pis-
ton-rod C and the cross-head pin b. A piece 55
of copper or other soft metal, c, is inserted be-
tween the fork of the block and the finished
surface of the pin b, to protect the latter from
being bruised. The bolt D is then screwed in
and the plug E forced out against the end of
60 the piston-rod C, and the latter forced out of
its socket, as shown in Fig. 3. If the plug E
proves too short for its purpose, or the space
will permit, the arrangement shown in Fig. 4 65
can be used. The bolt D is screwed back, and
the two plugs E and e pushed in, and the whole
adjusted so as to bring the fork of the plug e
against the copper c and cross-head pin b, and
the plug E against the piston-rod C, when, 70
upon screwing in the bolt D, both plugs E and
e are simultaneously driven out, forcing the
piston-rod twice as far out as can be done with
the single plug E, as described.

This jack can also be applied to a lathe for
75 straightening rods or shafting, and will be
found very useful for many other purposes.

Having thus described my invention, what I
claim as new, and desire to secure by Letters
80 Patent, is—

1. The combination, with a cone - pointed
screw, a nut in which it works, and means to
take the wedge - strain, substantially as de-
scribed.

2. The combination of the screw D, having 85
the conical point d, the internally-threaded
metallic block A, having a hole in one side,
and the movable plug E, fitting in said hole,
whereby the whole device may be arranged be-
tween the cross-head pin and piston-rod of a 90
steam-engine, to operate as described.

SAMUEL J. WISDOM.
